UNITED STATES PATENT OFFICE.

WATKIN G. POWELL, WILLIAM B. POWELL, AND JAMES L. POWELL, OF SHADELAND, PENNSYLVANIA.

WIRE HINGE.

No. 839,197.

Specification of Letters Patent.

Patented Dec. 25, 1906.

Application filed February 8, 1906. Serial No. 299,345.

To all whom it may concern:

Be it known that we, WATKIN G. POWELL, WILLIAM B. POWELL, and JAMES L. POWELL, citizens of the United States, residing at 5 Shadeland, in the county of Crawford and State of Pennsylvania, have invented certain new and useful Improvements in Wire Hinges, of which the following is a specification.

- 10 Our invention relates to improvements in hinges for doors, gates, windows, boxes, &c., in which wire is employed to construct the members or parts of the hinge; and some of the objects of our improvement are, first, to 15 provide a strong and durable article which is at the same time very light; second, to provide a hinge which may be hung with nails as well as screws, and thereby to lessen the time to hang it; third, to provide a hinge which 20 may be attached more firmly and securely than the ordinary leaf-hinge; fourth, to provide against rust due to accumulation of water or moisture about the pintle or other parts; fifth, to provide sufficient elasticity for 25 all parts to compensate for anything which may be caught between door and door-post and prevent breakage of hinge, and, sixth, to provide against the strain resulting in withdrawal of the nails or screws. We attain 30 these objects by the mechanism illustrated in the accompanying drawings, in which—

Figure 1 is a front elevation of the hinge applied to door and post. Fig. 2 is a transverse sectional view on the line 2 2 of Fig. 1. Fig. 3 is a rear elevation with the door partially open.

Similar letters refer to similar parts throughout the several views.

In constructing the hinge we employ two 40 pieces of wire, preferably galvanized and of length and size suitable for the purpose of the hinge and near their middle bent to form the eyes a and b . The parts of the wire a' a' and b' b' are forked at an acute angle and at a 45 suitable distance from the eyes are intercoiled around a double-headed pintle P in the same direction, as shown at a^2 a^2 and b^2 b^2 . The respective ends a^3 a^3 and b^3 b^3 are extended from the opposite ends of the pintle in the 50 same direction and plane with their respective parts a' a' and b' b' and bent twice and in opposite directions to form the eyes a^4 a^5 a^4 a^5 and b^4 b^5 b^4 b^5 . The construction described thus far forms the hinge members A

and B, which are to be secured to the outside 55 of door and post X and Y. Two shorter pieces C and D of the same kind of wire are similarly intercoiled about the pintle between the coils a^2 a^2 and b^2 b^2 , and their ends are bent to form the twin eyes c' c^2 c' c^2 and 60 d' d^2 d' d^2 , similar to the eyes a^4 a^5 and b^4 b^5 . The four sections of the hinge thus constructed are retained upon the pintle by the integral heads p p thereof, and the method of construction employed—that is, coiling the 65 members about the pintle instead of passing the pintle through coils already formed—permits the use of a pintle made with integral heads on the ends. This avoids the use of a nut or other easily-displaced retaining device 70 or upsetting of the end to form a sort of head, the object being to do away with tools in the hanging of this hinge where possible. This hinge is secured to the door and post by nails or screws, preferably nails, as shown in the 75 drawings at n . The members A and B are secured upon the outside, and the eyes of parts C and D are secured upon the abutting edges of the door and post, the edges being 80 suitably recessed, as at x and y , to accommodate the same.

By the construction thus described the strain or pull of the door, gate, or whatever is hung is always at right angles or transverse to the nails or screws which hold the hinge in 85 place and never pulls longitudinally on them. When the door, for example, is closed, the weight exerts its effect transversely upon the nails or screws on the outside of door and post, and when open the strain is exerted transversely on the fastening devices, whether nails or screws, in the edge of door and post. When the door is just ajar or standing at an angle to the post, the strain is divided between the fastening devices in the edges of 90 door and post and on the outside and is therefore still transversely of each nail or screw. This hinge may be quickly attached without much labor, nails and hammer only being employed, and when in place presents a very 95 neat appearance. Water accumulating in an ordinary hinge will quickly dry out of this hinge, and thereby prevent rusting.

The construction of the twin eyes to receive two fastening devices prevents the lateral strain from displacing them, as the S-shaped design forms a staple of the end of the wire and prevents the same from straight-

ening out. Another feature of the invention is the increased amount of wearing and bearing surface provided by the coils around the pintle, and as these present no angular edges 5 contacting with each other the life of the hinge is prolonged. Many other objects and advantages over the ordinary hinge will become apparent from the drawings.

Having thus fully described our invention, 10 what we claim as new, and desire to secure by Letters Patent, is—

In a wire hinge, the combination with a pintle, of two members pivotally attached thereto, said members being extended outward from the pintle and bent to form eyes 15 for the reception of fastening devices, the ends of said members being extended each a shorter distance and in the same plane with their middle portions and bent substan-

tially S-shaped to form twin eyes for the reception of fastening devices, two independent members pivotally attached to said pintle and adapted to be set at right angles to the first-mentioned members when the hinge is hung, the ends of said independent members being extended from the pintle a short distance and bent substantially S-shaped to form twin eyes for the reception of fastening devices, 20 substantially as described. 25

In testimony whereof we affix our signatures in presence of two witnesses.
